H. D. COTTRELL

LOOSE LEAF BINDER

Filed Jan. 19, 1925

Patented Aug. 25, 1925.

1,551,287

UNITED STATES PATENT OFFICE.

HOLLAND D. COTTRELL, OF DETROIT, MICHIGAN.

LOOSE-LEAF BINDER.

Application filed January 19, 1925. Serial No. 3,285.

To all whom it may concern:

Be it known that I, HOLLAND D. COTTRELL, a citizen of the United States, and residing at Detroit, in the county of Wayne and 5 State of Michigan, have invented a new and Improved Loose-Leaf Binder, of which the following is a specification.

This invention relates to loose leaf binders and the object of the invention is to provide 10 a loose leaf binder from which the leaves may be easily removed or replaced.

Another object of the invention is to provide a loose leaf binder which will fold compactly and will take up less storage 15 space than the ordinary types of loose leaf binders.

Another object of the invention is to provide a loose leaf binder in which the binding mechanism may be readily unlocked to allow 20 insertion of new leaves and may be quickly locked again to hold the leaves in place.

A further object of the invention is to provide a loose leaf binder of the character 25 described which is composed of few parts which are of low cost thus producing an efficient binder at a very low price.

These objects and the several novel features of the invention are hereinafter more 30 fully described and claimed and the preferred form of construction by which these objects are attained is shown in the accompanying drawings in which—

Fig. 1 is a perspective view of a loose 35 leaf binder embodying my invention.

Fig. 2 is a longitudinal section there- 40 through.

Fig. 3 is a section through the binder in the open position.

Fig. 4 shows the manner in which the leaves are unlocked for removal or replacement.

Fig. 5 is a detail of the locking device.

Fig. 6 is a section taken on line 6—6 of 45 Fig. 5.

Fig. 7 is a detail of one of the leaves used in the binder.

The binder comprises a cardboard cover folded to provide the two sides 1 and 2. 50 The cover 2 is folded to bend outwardly on the line 3 and a pair of fabric straps 4 and 5 extend outwardly through the cover 2 and are glued thereto at the points 6. A fabric strip 14 is pasted over the folded edge of 55 the binder and secures the ends of the strips 4 and 5 securely to the outer cover of the

binder. The opposite ends of the fabric straps 4 and 5 are secured beneath the in-turned flap 7 of the cover 1 by the clips 8 which extend through the cover 1, flap 7 and straps 4 and 5 as shown more particularly in Figs. 2 and 5. The straps 4 and 5 extend through apertures 16 provided therefor in a cardboard sheet 9 and this cardboard sheet 9 normally lays over the straps 4 and 5 and is provided with an extension 10 which engages beneath the flap 7 between the straps 4 and 5 as shown in Fig. 5. This cardboard sheet 9 is provided with an aperture 11 into which the finger may be inserted for disengaging the cardboard sheet 9 from beneath the flap 7. The cardboard sheet 9 normally lays flat against the inside of the cover 1 when the portion 10 thereof is engaged beneath the flap 7. The paper sheets are provided with notches 12 as shown in Fig. 7 to receive the straps 4 and 5, there being a plurality of paper sheets 13 held in the binder in this manner. At this time the binder may be opened as shown in Fig. 3 without loosening the paper sheets from the binder. To unlock the binding device and allow removal of the paper sheets the finger is inserted in the aperture 11 and the portion 10 is disengaged from beneath the flap 7 at 80 which time the cardboard sheet 9 may be moved to the position shown in Fig. 4 thus allowing the paper sheets to come out of the fold of the binder at which time the sheets may be removed from the straps 4 and 5 or new sheets may be placed thereon. At 85 this time the binder may be folded shut and the cardboard sheet 9 moved back to the position shown in Figs. 2 and 5 which moves the sheets back to the former position in the fold of the binder and locks them in place as shown in Fig. 2. It will thus be seen that the sheets may be easily removed from or replaced in the binder and when locked in the binder cannot be withdrawn without first disengaging the cardboard sheet 9. This device is very cheap to manufacture and having no extensions on the sides the binders may be stacked in a small 90 amount of space.

From the foregoing description it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

- 5 1. A loose leaf binder comprising a back and a front cover member hinged together, the back cover member being provided with an inturned flap at the outer edge, a pair of straps secured in spaced relation at one 10 end between the back cover member and the flap and being secured at the opposite end to the front cover member adjacent the hinge, a series of paper sheets notched to fit over the straps, a semi-flexible cardboard 15 retaining member having apertures at one edge through which the straps extend and being slidable on the straps to bindingly engage the sheets between the retainer member and the front cover member, a tongue 20 on one edge of the retaining member engaging beneath the flap between the straps to hold the retaining member in the binding position, the retaining member being of the same shape as the back cover member and 25 being provided with an aperture by means of which the retaining member may be grasped for disengaging the tongue of the retaining member from beneath the flap.
2. A loose leaf binder comprising a back 30 and a front cover member hinged together, the back cover member being provided with an inturned flap at the outer edge, a pair of straps secured at one end between the back cover member and the flap and being 35 secured at the opposite end to the front cover member adjacent the hinge, a series of paper sheets notched to fit over the straps, a semi-flexible retaining member 40 slidable on the straps to bindingly engage the sheets between the retaining member and the front cover member, and a tongue on the retaining member engaging beneath the flap between the straps to hold the retaining member in the binding position.
- 45 3. A loose leaf binder comprising a back and a front cover member of flexible material hinged together, a pair of straps secured to the outer edge of the back cover member at one end and secured at the opposite end 50 to the front cover member adjacent the hinge, a series of paper sheets notched to fit over the straps, a retaining member of

flexible material through which the straps extend, the retaining member being slidable on the straps to bindingly engage the sheets 55 between the retaining member and the front cover member, and means on the back cover member adapted to be engaged by the retaining member when in binding position to secure it in place.

4. A loose leaf binder comprising a back and a front cover member hinged together, the back cover member being provided with an inturned flap at the outer edge, a pair of straps secured beneath the said flap at one 65 end and secured at the opposite end to the front cover member adjacent the hinge, a series of sheets notched to fit over the straps, a retaining member slidable on the straps to bindingly engage the sheets between the retaining member and the front cover member, and a tongue on the retaining member engaging beneath the said flap to hold the retaining member in the binding position.

5. A loose leaf binder comprising a back 75 and a front cover member hinged together, a pair of straps secured to the outer edge of the back cover member at one end and secured at the opposite end to the front cover member adjacent the hinge, a series 80 of paper sheets notched to fit over the straps, and a retaining member slidable on the straps to bindingly engage the sheets between the retaining member and the front cover member, an inturned flap on the back cover member, and a tongue on the retaining member adapted to engage beneath the inturned flap to hold the retaining member in binding position.

6. A loose leaf binder comprising a back 90 and a front cover member hinged together, a pair of straps secured to the outer edge of the back cover member at one end and secured at the opposite end to the front cover member adjacent the hinge, a series of paper 95 sheets notched to fit over the straps, a retaining member slidable on the straps to bindingly engage the sheets between the retaining member and the front cover member, and means for securing the retaining member in binding position.

In testimony whereof I sign this specification.

HOLLAND D. COTTRELL.
